UNITED STATES PATENT OFFICE

ERICH SCHULZE, OF HANOVER, GERMANY, ASSIGNOR TO KARL SCHRADER, OF HANOVER, GERMANY

MANUFACTURING PERMANENTLY-STERILE INJECTION LIQUIDS

No Drawing. Application filed July 23, 1925, Serial No. 45,717, and in Germany July 23, 1924.

This invention has reference to the manufacture of injection or other liquids for dental, medicinal and other purposes, and particularly for local anaesthesia by means of which practically permanent injection liquids 5 proof against the action of bacteria, as well as against other infecting agents, such as schizomycetes, fungus growth, putrefaction and the like are obtained, and 10 without the objectionable, irritating and other injurious action heretofore experienced with a great many of the solutions referred to. The sterilization of injection liquids, particularly for subcutaneous use or 15 local anaesthesia was heretofore effected mostly by mechanical or physical means or by the addition of such substances, such as phenol, cresol, thymol and the like which produced serious irritating action and in- 20 jury to the tissue and were also open to other objectionable action; nor was it possible to arrive at a reliable permanent sterilization by the means referred to. Thus for instance, the small bulbs or "ampoules", and the like 25 now in use and filled with the most varying kinds of injection liquid and sterilized by mechanical or physical means, while by themselves sterile under certain conditions, have been known to soon lose their absolute 30 freedom from germs after being opened either by infection from the tool employed in opening them or, by the entrance of air containing bacteria, or by the introduction of an injector which is not absolutely free 35 from germs. While with the judicious and most careful employment of special kinds of injection needles, draining needles, tubings or "canules," extensions and the like, it has been possible to prevent any most serious 40 contamination of the solution, yet, a perfect and permanent sterilization of the solution could never be depended upon, and as a matter of fact the presence of micro-organisms with the use of the processes here- 45 tofore employed has been ascertained and proved in many cases.

Now, my invention has reference to a method by means of which it is possible to produce an absolutely reliable permanent 50 sterility of injection liquids without inter-

ferring with their keeping qualities and their composition, and particularly in the case of injection liquids for local anaesthesia, such as for example, novocain solutions that is to say solutions of para-amino-benzoyl-di- 55 ethyl-amino-ethanol-hydrochloride of the usual composition, by making an addition of small amounts of certain quinine-alkaloids, to which in certain cases carbolic acid or phenol or benzoic acid or a mixture of the same or homologues may be added. Of the alkaloids referred to it has been ascertained that particularly the alkyl-compounds of the hydro-quinine with from 5 to 8 atoms of carbon in the lateral chain of 60 the quinoline-nucleus are highly efficient for the purpose in question, such as for instance the eucupine or iso-amyl-hydrocupreine, and the vuzine or iso-octyl-hydrocupreine, and furthermore those compounds obtained 65 by the splitting up of the quinoline-nucleus by prolonged heating with acetic acid and containing the carbonyl group C=O and designated as quina toxines in view of their specific poisonous action upon micro-organisms, and of these particularly the vuzinotoxine has been found to be particularly suitable. These compounds are also scientifically designated as "hydrocupreicines" 70 (compare Henry, Plant-Alkaloids 1924, page 75 80 171), the quinatoxine product obtained from vuzin being scientifically termed iso-octyl-hydrocupreicaine, these bodies being moreover derivatives of quinicaine. It has been ascertained from the specific poisonous action 85 of these compounds against micro-organisms that these compounds may be employed in such minute quantities for the purpose of producing by themselves absolute permanent sterilization in injection solutions that any liability of irritation of the tissue, and of excitation of the patient consequent thereon are excluded.

In further pursuance of my invention the sterility and activity of these quinine-alkaloids, particularly in the case of protection from putrefaction germs, schizomycetes and the like, and from the action of ferment may be further increased by the treatment with very small quantities of carbolic acid or 100

phenols or with benzoic acid or with both of them combined.

While the employment of carbolic acid as a sterilizing addition to injection solutions is by itself known, such addition was made heretofore in such concentrations that it was relied upon to be able to act as a bactericide itself, that is to say in concentrations of 2% and above. In such concentrations, however, the carbolic acid produces very serious injuries to the tissue and irritation, inasmuch as a two-percent solution is already injurious to the fibers and cellules of the animal nerves. Now, it is a very important element of my invention that the carbolic acid is employed at a considerably lower concentration, in which concentration the carbolic acid is not any more able to kill the bacteria, while it will yet produce a preventing or retarding action upon the decomposition of the organisms which have been killed by vuzinotoxin (or iso-octyl-hydro-cupreine-toxine) or the like, and thereby also prevents all liability of the formation of mould. It has been ascertained by a series of tests that an addition of three drops (about 0.06 grams) carbolic acid to 100 cc. of an injection solution, for instance to a solution of 2 to 4% of novocain, to which has been added one drop of a 10% alcoholic solution of vuzinotoxin-hydrochlorid, is already sufficient to obtain a perfectly and permanently sterile injection solution of excellent keeping qualities, and not subject to decomposition or to the formation of mould, while perfectly agreeing with and not injurious to the animal tissues.

The carbolic acid or phenols may be replaced or be used in conjunction with benzoic acid, the solution and addition of benzoic acid being likewise employed in such small quantities that the benzoic acid is neither sufficient as a bactericide nor destructive to the tissue. It is, for instance, sufficient to add benzoic acid to a solution of novocain to which has been previously added one drop amounting to about a minim or say about 0.07 cc. of a 10% solution of vuzinotoxin hydrochlorid in alcohol, 0.1 to 0.2% of benzoic acid being added in order to obtain a perfectly and permanently sterile and keeping injection solution which is not subject to decomposition, putrefaction or formation of mould, and which is suitable and perfectly agreeing even with the most delicate and sensible tissues and persons.

Where there is no necessity of paying special attention to the presence of putrefaction bacteria, it is in most cases sufficient to merely add a small amount of the toxine to the solution to be protected, and in this case I may, for instance, proceed as follows:—

A 2 to 4% solution of novocain is treated with about one drop amounting to about a minim or say about 0.07 cc. of a ten percent alcoholic solution of vuzinotoxin

hydrochlorid. It is obvious that the concentration may be varied in accordance with particular requirements.

It should also be pointed out in this connection that the invention may find expression in many other embodiments to better adapt the same to varying conditions of application, and that changes and modifications are possible within the spirit and scope of my invention, as particularly set forth in the appended claims.

By this means injection solutions are obtained both for dental as well as for general medicinal and surgical uses.

I claim:—

1. An injection liquid containing an novocaine and a small quantity of a solution of vuzino-quina-alkaloid.

2. An injection solution of high sterility, containing very small quantities averaging up to about 2 to 3-hundredths of a gram of hydro-cupreicines in 100 cc.

3. An injection solution of high sterility, containing very small quantities averaging up to about 2 to 3-hundredths of a gram of iso-hydro-octyl-cupreicine in 100 cc.

4. An injection liquid, containing very small quantities averaging up to about 2 to 3-hundredths of a gram of hydrocupreicine-alkaloids in 100 cc. and such small quantities of oxy-benzols of acid reaction, as will exclude irritative and destructive action on animal tissues.

5. An injection liquid of high sterility, containing on an average up to about 2 to 3-hundredths of a gram of the hydrochlorid of hydrocupreicines.

6. An injection liquid of high sterility, containing on an average up to about 2 to 3-hundredths of a gram of iso-octyl-hydrocupreicine in one hundred part of liquid.

7. An injection liquid of high sterility, containing on an average up to about 2 to 3-hundredths of a gram of iso-octyl-hydrocupreicine-hydrochlorid and tenths of a gram of oxy-benzols of acid reaction to one hundred parts of liquid.

8. An injection liquid containing novocaine and a small quantity of up to 2 to 3-hundredths of a gram to hundred parts of liquid on an average of an alcoholic solution of iso-octyl-hydrocupreicine-hydrochlorid.

ERICH SCHULZE.
